UNITED STATES PATENT OFFICE.

ROBERT WILLOUGHBY Vining, of Ealing, England, assignor to Auto-Postergraph Syndicate, Limited, of London, England.

ADVERTISING DEVICE.

SPECIFICATION forming part of Letters Patent No. 692,950, dated February 11, 1902.

Application filed September 5, 1901. Serial No. 74,392. (No model.)

To all whom it may concern:

Be it known that I, ROBERT WILLOUGHBY Vining, a subject of the King of Great Britain, residing at Ealing, in the county of Middlesex, England, have invented a new and useful Improvement in Advertising Devices, (for which I have made application for Letters Patent in Great Britain under No. 2,600 and date February 6, 1901,) of which the following is a specification.

This invention relates to advertising devices, and has for its object the construction and arrangement of apparatus whereby a window or other available space can be utilized for advertisement in the day-time by means of printed or pictorial matter of a permanent nature and at night by means of a series of pictures projected by an optical lantern upon a screen, the whole being made automatic in its operation through the means of electricity, water, or other motive power and controlled by a time mechanism, so as to require no other attention than the winding up of the clock at predetermined periods—say once a week.

In order that the invention may be the better understood, I will now proceed to describe it in relation to the accompanying drawings, reference being had to the letters marked thereon.

Like letters refer to like parts in the various views.

Figure 1 is a view showing the general arrangement of my apparatus in an apartment. Fig. 2 is a diagrammatic view of the timing mechanism, control-switches, and electrical circuits. Fig. 3 is a rear elevation of the projecting apparatus and its operative mechanism. Fig. 4 is a plan of the same. Fig. 5 is a front elevation of the same. Fig. 6 is a side elevation. Fig. 7 is a detail view of the motor main switch mechanism. Fig. 8 is a detail view of the lamp switch mechanism. Fig. 9 is a detail view of the four-way switch mechanism. Fig. 10 is a front view of the shutter mechanism shown in Fig. 6.

In order to carry my invention into effect, I arrange a translucent screen *a* in front of the window or other position upon which the projected pictures by the optical lantern are made, and in front of this screen *a* I arrange a roller-blind *b* or the like, upon the front sur-

face of which is placed the permanent matter for advertisement. The roller-blind *b* is drawn up and lowered by means of a cord *c*, wound around a drum *d*, operated by the control mechanism *e*, the movements of which are controlled by the time mechanism *f*. The time mechanism is preferably a twenty-four-hour clock having two electrical contacts *g* *g'* on its face and a contact-finger *g''*, carried by the clockwork. The control mechanism *e* consists of an electromotor *h*, having a worm *e'* on its shaft, which gears into a worm-wheel *e''*, fixedly mounted on a shaft *j*. A cog-wheel *j'* is loosely mounted on the shaft *j* and is driven by means of a clutch *j''*. The cog-wheel *j'* gears with a cog-wheel *d'*, situated on the drum *d*, on one end thereof. A similar wheel *d''* is also carried by the drum *d* on the other end. Another cog-wheel *k* is loosely mounted on the shaft *j* and is driven by an intermediate cog-wheel *k'* from the cog-wheel *h*, so as to give a reverse motion to drum *d* to that given by the cog-wheel *j'*. The motion in this case is transmitted through a clutch *j'''*. The movements of the clutches *j''* and *j'''* are effected by means of a grooved sliding sleeve *j'''* and spiral springs *j''''*, which are compressible in the event of the corresponding parts of clutch not being opposite to one another when the sleeve *j'''* is moved either to one side or the other, so as to force the said parts into engagement when the motor starts and rotates one part of the clutch relative to the other part. By this arrangement the drum can wind and unwind the blind, although the motor runs in the same direction always.

The drum-axle *d''* carries a cog-wheel *l*, which gears into a large cog-wheel *l'*, which is loosely journaled on the shaft *j* and has rigidly attached to it three cams *m* *m'* *m''*. The cam *m* operates a lever *n*, which works a spring-switch *o* of usual construction, which is the main control-switch for the current to the motor *h*. The cam *m'* operates a lever *n'*, which works a spring-switch *o'* of usual construction for control of the current to the electric-arc lamp *o''* of the optical lantern. The cam *m''* operates directly upon the four-way switch *n''* in the electric circuit *o'''* of the electric control mechanism *r*. The control

mechanism r consists of two electromagnets r' r^2 , which are connected to a battery r^3 and to the contacts n^3 n^4 of the four-pole switch n^2 . The armatures of the electromagnets r' r^2 are mounted on a double-armed lever s , pivoted on the framework and carrying a third arm s' , extending downward. The central portion of this arm s' engages with the groove of the sliding sleeve j^4 , so that when 5 the arm is rocked about its axis it moves the sleeve either to one side or the other, as the case may be. The lower end of the arm s' engages with a projection s^2 on a pivoted lever s^3 when it is rocked to the right side and 10 is retained in that position thereby until released. The lever s has an upwardly-extending arm s^4 , having an adjustable contact-screw s^5 , adapted to operate a spring-switch t in the shunt-circuit t^2 from the main circuit 15 t^2 to the motor h and is used merely for the purpose of starting up the motor h . The arm s' is released from engagement with the pivoted lever s^3 by means of a lever t^5 , pivoted on a bracket t^3 , the end of the lever t^5 engaging 20 the arm s' , so as to depress the same when engaged by a pin t^4 on the wheel t' . The battery r^3 is connected to the contact-finger g^2 of the timing mechanism, and the contacts g^3 thereof are connected to the contacts n^5 n^6 25 of the switch n^2 .

The lantern-slides u are carried around the periphery of a large wheel u' , to which an intermittent motion is given by the electromotor by means of a gear consisting of a cam u^2 , 30 carried at the end of the axle j . This cam u^2 is adapted to oscillate the lever u^3 , which latter carries a spring-pressed pawl u^4 , situated so as to engage with pins u^5 , situated around the wheel u' , the number of the pins being 35 the same as the number of lantern-slides u around the wheel. The lever u^3 is arranged so that it is moved on its backward stroke by the cam u^2 and on the forward stroke to move the wheel u' , which is effected entirely 40 by a spring u^6 , attached at one end to the lever u^3 . In order to insure a correct register of the lantern-slides in front of the projecting-lens, I pivot a weighted lever v on the framework, the said lever having a semicircular recess v' , adapted to engage one of the pins u^5 at the end of each intermittent movement of the wheel u' .

In order to prevent a movable image on the screen a during the change of position of the lantern-slides, I provide an oscillating shutter w to act as an occultator. This shutter w is operated from a cam w' , carried by the shaft j , pivoted lever w^2 , connecting-rod w^3 , lever w^4 , and axle w^5 , the shutter w being 55 fixedly carried by the latter.

The operation of my device is as follows: It is assumed that the timing mechanism f is wound up and going, the main circuit t^2 is connected to a source of electric current, and 60 the machine is in its quiescent condition, such as in the day-time, when the permanent advertisement is exhibited on the blind b .

As soon as the contact-finger g^2 touches the contact g a current passes from the battery r^3 to the electromagnet r' , drawing down its armature and the lever s . This action makes the electrical shunt-circuit t^2 and allows current to pass to the motor to start it, and simultaneously the lever s' pushes the sleeve j^4 to the right, so as to make the clutch j^3 engage the wheel k . The motor then gradually rolls up the blind and also causes the cam m to operate the lever n and close the main motor-switch o . When the blind is nearly at the top, the cam m' operates the lever n' and closes the switch o' of the arc-lamp. At the same time the cam m^2 moves the four-way switch n^2 over to the other contacts n^3 n^6 , so that the battery r^3 will not run down, as the contacts on the timing mechanism are not 85 broken for some five to ten minutes, as the movement is so slow. Just as the blind is wound up the pin t^4 on the wheel t' engages the lever s^3 , depresses it, and allows the arm s' to be disengaged from the projection s^2 90 and to assume its normal central position, which is effected by the two adjustable springs s^6 , one being on each side of the arm s^4 . This action immediately pulls the clutch j^3 out of engagement with the wheel k . The motor 95 then continues to operate the wheel u' by means of the lever u^3 and pawl u^4 , the cam w' moving the shutter w so as to obscure the picture during the movement of the lantern-slides. When the contact-finger g^2 of the 100 timing mechanism f makes electrical connection with the contacts n^3 n^6 , the electromagnet r^2 is energized, and the lever s' puts the clutch j^3 into gear with the wheel j' , the blind b is unrolled, the arc-lamp switched off, and 105 the four-way switch n^2 is returned to its original position, and finally the current is switched off from the motor, the arm s' returning to its central normal position ready for the next period of operation.

Although I have described my invention as being operated by an electric motor and illuminated by an electric lamp, it is quite obvious any other motor and illuminating agent can be used by substituting equivalent control devices in substitution of the electric switches t , o , and o' . I may make the screen a as a roller-blind, which can unroll when the roller-blind b is being wound up, and vice versa.

Having now described my invention, what I claim, and desire to secure by Letters Patent, is—

An advertising device consisting of in combination, an optical projecting apparatus, a translucent screen arranged to receive the image projected thereby, a rotating lantern-slide carrier, means for giving the said carrier an intermittent motion from continuous motion, a uniform-speeded motor for driving the machine, a timing mechanism having electrical contacts, an electrical control mechanism controlled by the timing mechanism, a roller-blind carrying permanent advertis-

ing matter, a winding mechanism adapted to roll up and unroll the said blind, a reversing and disengaging mechanism connecting the motor with the winding mechanism, means operated by the electrical control device adapted to effect the reversing and disengaging mechanism, and a mechanical controlling device operated by the winding mechanism adapted to control the supply of energy to the

motor and of the lighting agent to the optical lantern, substantially as described.

In witness whereof I have hereunto set my hand in presence of two witnesses.

ROBERT WILLOUGHBY Vining.
